COUNTER SIRUP DISPENSER AND VALVE

Jack J. Booth, Dallas, Tex.

Application December 11, 1950, Serial No. 200,195

4 Claims. (Cl. 222—207)

1

This invention relates to fluid measuring and dispensing apparatus and more particularly to such apparatus designed to measure and dispense flavoring syrups used with carbonated water as beverages.

The principal object of the invention is to provide a measuring or metering valve for flavoring syrups which includes in its assembly a collapsible boot of "neoprene" or equivalent material which has a predetermined capacity, thus to measure a quantity of syrup drawn thereinto by the expanding action of a spring and which syrup is expelled from the boot into a waiting container under pressure of a plunger which collapses the boot.

Another object of the invention resides in the novel assembly of the valve head, boot housing, plunger and the boot which latter, when expanded, is adequately reinforced by the walls of its housing and is equipped with means cooperating with the boot and housing to positively seal the assembly against leakage. Moreover, certain reinforcing embedded in the boot insures a measure of rigidity in the head of the boot to hold its walls in flush engagement with the inner surfaces of the housing under tension of the expanding spring so that full measure of fluid will be drawn into the boot each time it is expanded.

Still another object of the invention is to provide a vessel in separate sections adapted to enclose a syrup container, usually a jug, which is inverted in the lower section of the vessel, to which latter is connected the measuring and dispensing valve of the invention. The mouth of the jug is supported by an embossed rib in the bottom of the lower vessel section to permit the contents of the jug to flow into the said lower section until its level rises to seal the mouth of the jug. A pick-up tube extends from the dispensing valve to a point in the vessel below the embossed rib to transfer syrup to the valve.

Other objects will appear as the description proceeds, taken in connection with the accompanying drawing, wherein:

Figure 1 is a side elevational view of a sectional vessel with a portion broken away and showing the measuring and dispensing valve connected thereto.

Figure 2 is a longitudinal sectional view of the valve per se.

Figure 3 is a transverse sectional view taken on line 3—3 of Figure 2, and

Figure 4 is a sectional view taken on line 4—4 of Figure 2.

Continuing with a more detailed description

2

of the drawing, reference numeral 10 denotes the lower section of a capsule type vessel, on which is disposed the upper section 11. The lower section 10 has an annular bead 12 about its upper end which serves as a stop for the expanded end 13 of the upper section 11 which frictionally engages the upper end of the lower section, thus sealing out all foreign matter to keep the contents of the vessel in a sanitary condition.

10 The bottom of the lower vessel section 10 has a circular depression 14 which elevates the central portion of the bottom and defines an annular trough 15 into which depends the pick-up tube 16 of the measuring and dispensing valve which will be described presently. The elevated central portion 15 of the vessel bottom is embossed to provide a rib 17 on which is adapted to rest the mouth of a jug 18 which is inverted in the lower section 10. The rib 17 is of greater 20 length than width so that fluid will flow from the mouth of the jug on each side of the rib until the level of the liquid rises to close the mouth of the jug. This level is, of course, maintained until the jug is emptied.

23 The vessel, constructed in the manner shown, is usually provided with a suitable clamp (not shown) by which it is secured to a counter or table top for the convenient drawing of flavoring syrup with which is mixed carbonated water and ice to produce a beverage. To accomplish this, a valve generally indicated by reference numeral 19, is attached to the pick-up tube 16 which latter emerges from the lower section 10 of the vessel and extends to a point near the top thereof, the portion of the tube intermediate its ends being secured, as by soldering or welding, to the side of the section 10.

The valve 19 consists of a head 20 which has a recess in one end provided with internal threads engaging the external threads of a cylindrical housing 21. Both ends of the housing are open, the outer end being provided with an annular internal flange 22 under which is the external flange 23 of a plunger 24 and limits outward displacement of the plunger. The inner end of the cylinder 21 is exteriorly chamfered at a (Fig. 2) to be received in an annular channel formed in an external flange 25 provided on the open end of a boot 26, made of "neoprene," due to the latter's invulnerability to attack by various chemicals in fluids and since it does not alter the taste of the fluid as does natural rubber.

The anchorage afforded by the chamfered end 55 of the cylinder 21, which constitutes the boot

housing, and the flange 25 of the boot, there is no leakage of suction or liquid at the juncture between the boot, boot housing and valve head 20. The outer end of the boot is closed and is reinforced by a fabric disc 27 embedded therein. Reinforcing of the boot end prevents folding in of its walls and holds the walls at all times flush against the inner surfaces of the housing 21. This insures against short measure of flavoring syrup since the capacity of the boot, in the present case, is one ounce, the quantity prescribed by syrup manufacturers for six ounce drink.

The inner face of the end of the boot 26 has a circular embossed area 28 which retains in position one end of a coil spring 29, the opposite end of the spring lying in an annular groove *a'* in the inner face of the valve head 20 and surrounding a circular boss 30 formed on the head. Thus, the spring 29 is collapsed in the groove *a'* and does not pinch the side walls of the boot 26 and in expanding returns the boot 26 to expanded position each time it is collapsed by inward thrust of the plunger 24 to expel fluid drawn thereinto by suction.

Fluid enters the boot 26 through the pick-up tube 16 whose upper end 31 is threaded for reception by a threaded axial bore in the head 20, the bore continuing, in reduced diameter, into the chamber occupied by the boot 26. The end of the tube 16 has a conical recess 32 which contains a ball valve 33, the small end of the recess providing a seat for the ball to prevent return of fluid through the tube 16 when the plunger 24 is depressed to expel fluid from the boot. It will be observed in Figure 4 that the end of the bore 32 where it emerges into the boot housing has formed therein diametrically opposed protuberances *b* which limit forward displacement of the ball 33 but do not interfere with free passage of fluid into the boot.

Below the inlet bore 32 is a fluid outlet passage 34, in control of which is a ball valve 35 under pressure of a coil spring 36 which urges the ball upwardly against its seat 37. The ball 35 and its spring are arranged in a tubular spout 38 which is threaded at its upper end into a threaded opening in the valve head 20, against the rubber valve seat 37 to hold the latter in place. The outer surface of the spout 38 is knurled at 39 to facilitate its installation and removal.

The lower section 40 of the vessel is secured to a table top or counter and the jug of syrup is inverted therein as described. The top section 41 is placed on the lower section and the plunger 24 of valve 19 is reciprocated until the suction fills the pick-up tube 16 and the boot 26. The plunger 24 is pushed inwardly to collapse the boot, thus forcing the syrup therein past the valve 35 and through the spout 38 into a cup or glass held thereunder which is then filled with carbonated water or other described mix. When the plunger 24 is retracted by the spring 29, the boot 26 will resume its expanded position and the suction created therein and within the pick-up tube 16 will refill the boot preparatory to another dispensing operation.

Manifestly, the construction as shown and described is capable of some modification and such modification as may be construed to fall within the scope and meaning of the appended claims is also considered to be within the spirit and intent of the invention.

What is claimed is:

1. A fluid measuring and dispensing apparatus comprising a vessel in separable, longitudinally

aligned sections, one of said sections having a bottom provided with a centrally elevated portion defining an annular trough, a rib embossed in said elevated portion, a fluid container inverted in said vessel and supported on said rib to release fluid into said trough, a fluid pick-up tube entering the side of said vessel whose lower end is disposed in said trough, a dispensing valve having a head threadedly attached to the upper end of said pick-up tube, a ball valve in said pick-up tube, a cylindrical housing attached to said valve head, a fluid quantity measuring boot of resilient material anchored at the juncture of said head and housing and disposed in said housing, a plunger for collapsing said boot in said housing, a spring for expanding said boot effective to create suction in said pick-up tube to displace said ball valve and to fill said boot with fluid, and valve controlled means for releasing fluid from said boot upon actuation of said plunger, said housing and said plunger limiting the degree of expansion of said boot and said head limiting the degree of collapse of said boot whereby a predetermined amount of liquid may be dispensed upon each reciprocation of said plunger.

2. In a liquid dispensing apparatus, an inverted liquid container, a liquid pick-up tube depending into said container and terminating exteriorly of said container midway of the ends of the latter, a dispensing valve comprising a tubular housing, a head attached to the outer end of said pick-up tube and threadedly connected to said housing, a collapsible flexible boot of substantially cup shape having an open end and a closed end, said open end being anchored at the threaded connection between said head and housing, means slidably in said tubular housing and contacting the closed end of said boot for collapsing said boot, said housing and said slidably means contacting the outer surfaces of said boot to limit its expansion, means for expanding said boot, valve means in said pick-up tube displaceable by suction created in the latter by the expanding action of said boot effective to fill said boot with liquid and valve controlled means for releasing liquid from said boot under pressure imposed by said boot collapsing means.

3. A fluid measuring and dispensing apparatus comprising a vessel in separable, longitudinally aligned sections, one of said sections having a bottom provided with a centrally elevated portion defining an annular trough, a rib embossed in said elevated portion, a fluid container inverted in said vessel and supported on said rib to release fluid into said trough, a fluid pick-up tube entering the side of said vessel whose lower end is disposed in said trough, and a manually operable pump means connected to the upper end of said pick-up tube for dispensing liquid from said vessel in predetermined quantities.

4. A fluid measuring and dispensing apparatus comprising a vessel having a bottom provided with a centrally elevated portion defining an annular trough, a rib embossed in said elevated portion, a fluid container inverted in said vessel and supported on said rib to release fluid into said trough, a fluid pick-up tube entering the side of said vessel whose lower end is disposed in said trough, and a manually operable pump means connected to the upper end of said pick-up tube for dispensing liquid from said vessel in predetermined quantities.
